(57) **CLAIM**

The ornamental design for a ground stake with articulating light clip, as shown.

DESCRIPTION

FIG. 1 is a perspective view of the ground stake with articulating light clip showing a top, a front and a right side of my new design;

FIG. 2 is a perspective view of the ground stake with articulating light clip showing a bottom, a rear and a left side of my new design;

FIG. 3 is the ground stake with articulating light clip showing the front view thereof;

FIG. 4 is the ground stake with articulating light clip showing the rear view thereof;

FIG. 5 is the ground stake with articulating light clip showing the right-side view thereof;

FIG. 6 is the ground stake with articulating light clip showing the left-side view thereof;

FIG. 7 is the ground stake with articulating light clip showing the top view thereof; and,

FIG. 8 is the ground stake with articulating light clip showing the bottom view thereof.

1 Claim, 7 Drawing Sheets
